[57] CLAIM

The ornamental design for a blood gas syringe stopper, substantially as shown and described.

DESCRIPTION

FIG. 1 is a top plan view of a blood gas syringe stopper showing my new design;
 FIG. 2 is a side view thereof;
 FIG. 3 is a bottom plan view thereof;
 FIG. 4 is a front isometric view taken at a reduced scale;
 FIG. 5 is a rear isometric view thereof;
 FIG. 6 is a sectional view at line 6—6 of FIG. 1; and
 FIG. 7 is a sectional view at line 7—7 of FIG. 2.
